(57) **CLAIM**

The ornamental design for a combination eyeglass retainer and earplug holder, as shown and described.

DESCRIPTION

FIG. 1 is a perspective view of the combination eyeglass retainer and earplug holder with a sheath partially retracted. FIG. 2 is a top side view of the combination eyeglass retainer and earplug holder.

FIG. 3 is a bottom side view of the combination eyeglass retainer and earplug holder.

FIG. 4 is a back view of the combination eyeglass retainer and earplug holder.

FIG. 5 is a front view of the combination eyeglass retainer and earplug holder.

FIG. 6 is a right side view of the combination eyeglass retainer and earplug holder.

FIG. 7 is a left side view of the combination eyeglass retainer and earplug holder; and,

FIG. 8 is a perspective view of the combination eyeglass retainer and earplug holder with the sheath extended.

The broken line portions of the eyeglass retainer are not part of the claimed design.

1 Claim, 8 Drawing Sheets
